Inventor
Charles Edgar Murphy,
By *Knapp & Cook*
Attorneys.

UNITED STATES PATENT OFFICE.

CHARLES EDGAR MURPHY, OF ST. LOUIS, MISSOURI, ASSIGNOR OF ONE-THIRD TO
FREDERICK C. KOETZLA AND ONE-THIRD TO WILLIAM G. CLARK, BOTH OF ST.
LOUIS, MISSOURI.

GAGE-COCK.

1,356,732.

Specification of Letters Patent. Patented Oct. 26, 1920.

Application filed May 24, 1919. Serial No. 299,633.

To all whom it may concern:

Be it known that I, CHARLES EDGAR MURPHY, a citizen of the United States of America, a resident of the city of St. Louis, 5 in the State of Missouri, have invented certain new and useful Improvements in Gage-Cocks, of which the following is a full, clear, and exact description, reference being had to the accompanying drawings, forming a 10 part of this specification.

My invention relates to a gage cock for use in connection with a steam boiler, and has for its object to provide a detachable valve tip in a cock of this kind, thereby 15 making it possible to renew the valve tip at a slight expense without renewal of the entire valve stem.

Figure I is a side elevation, partly in longitudinal section, of a gage cock 20 containing my invention.

Fig. II is a cross section taken on line II—II, Fig. I.

In the drawings, A designates a gage cock casing having a valve chamber B therein 25 provided with a valve seat C. The casing A has connected to it a usual stuffing box D, through which a valve stem E operates.

The parts thus far described are of common form, except for the structure of the 30 valve stem, as will be described.

In the inner end of the valve stem is a pocket 1, extending longitudinally of the stem. 2 designates a valve tip provided with a stem 3 removably arranged in the 35 pocket 1 in the valve stem E and held therein by a key 5, removably arranged in a transverse keyway in the wall surrounding the valve stem pocket 1, and seated in an annular groove 4 in the stem 3 of the valve 40 tip 2. The valve stem tip 2 is readily secured to the valve stem E upon the insertion of the key 5 into the valve stem, and the stem of the valve tip is so held to the valve stem as to perform its function as perfectly 45 as the function would be performed if the valve stem tip were an integral part of the valve stem. Whenever the valve stem tip becomes pitted or otherwise damaged in service, it may be quickly detached from the

valve stem and replaced by a new tip at a 50 minimum of expense as compared with the expense which would be involved by replacing a complete valve stem having a valve tip integral therewith, as commonly made.

By reference to Fig. I it will be seen that 55 the stem of the valve tip 2 is considerably smaller in diameter than the diameter of the pocket 1 in the valve stem. These differences in diameter permit lateral play of the valve tip stem relative to valve stem and 60 provide for the valve tip being positively presented to the valve seat C if the valve stem is not in direct alinement with the valve seat.

The key 5 by which the stem of the valve 65 tip 2 is detachably held in the pocket of the valve stem E is of semi-circular shape and is slipped through an opening in the wall surrounding the pocket in the stem, so that it enters the annular groove 4 in the stem 70 of the valve tip, and is spaced from the cylindrical wall thereof, so as to partly surround said valve tip stem with an engagement which effectually retains the valve tip and affords a wearing surface between the 75 stem of the tip and the key, which will not become impaired by long continued use.

I claim:

In a gage cock, a valve stem having a pocket therein at its inner end and a slotted 80 key way in the wall of said pocket, a valve tip having a stem positioned in said pocket, the stem of said valve tip being of a lesser diameter and length than said pocket, said valve tip stem being provided with an annular groove, and a semicircular key, having its outer periphery flush with the periphery of said valve stem, extending through said slotted key way to said pocket and seated in said annular groove and 85 spaced from the cylindrical wall thereof, so as to partially surround the stem of the valve tip, whereby said valve tip is freely rotatable and has lateral and longitudinal play in said pocket.

In testimony that I claim the foregoing I hereunto affix my signature.

CHARLES EDGAR MURPHY.
